UNITED STATES PATENT OFFICE.

DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,330,221.

Specification of Letters Patent. Patented Feb. 10, 1920.

Application filed January 4, 1918. Serial No. 210,243.

To all whom it may concern:

Be it known that I, DAWSON M. TAGGART, a citizen of the United States, residing at East Orange, in the county of Essex and 5 State of New Jersey, have invented certain new and useful Improvements in Telephone-Exchange Systems, of which the following is a full, clear, concise, and exact description.

10 This invention relates to telephone exchange systems, and more particularly to such systems in which a plurality of common battery and local battery telephone lines terminating at a central office may be 15 interconnected by means of link circuits located thereat.

The object of this invention is to provide improved signaling means for systems of this character.

20 In accordance with this invention a link circuit is provided with a relay energized when connected with a telephone line, while the supervisory relay of the link circuit is deenergized, to maintain the initial energizing circuit of a recall control relay open, and, after the response of the called-for subscriber, coöperates with the recall control relay and the supervisory relay, to cause the 25 intermittent operation of a supervisory signaling device upon the initiation of a recall 30 by the subscriber.

This invention will be more fully understood from the following description considered in connection with the accompanying 35 drawing illustrating one embodiment thereof.

There is shown in the drawing a telephone line A of the usual common battery type, which extends from a subscriber's station to 40 a central office at which it terminates. A local battery telephone line B also terminates at the same central office, at which is located a universal cord circuit C, employed for interconnecting these two types of lines.

45 It is believed that this invention is of such a nature that it can best be understood from a description of the operation of the system shown in the drawing, and it will be so described.

50 Subscriber A, in initiating a call, removes the receiver from the switchhook, thereby causing the operation of line relay 5 and the lighting of line lamp 6. The operator, upon

observing the lighted condition of the line lamp 6, inserts plug 7 of the cord circuit C 55 into jack 8 of line A, thereby causing the operation of relay 9, marginal relay 10 and cutoff relay 11, over a circuit from battery, through the left-hand winding of relay 9, the winding of relay 10, sleeve contacts of 60 the plug 7 and the jack 8, and the winding of cutoff relay 11 to ground. Marginal relay 10 operates when included in circuit with a low resistance cutoff relay of a common battery line, but does not operate when included in circuit with a high-resistance cutoff relay of a local battery line. Cutoff relay 11, in operating, disconnects the line relay 5 from the line, thereby extinguishing the line lamp 6. Marginal relay 10 in operating, disconnects the two windings of supervisory relay 15 from across the talking strands of the cord circuit C, and connects the tip strand to ground through the right-hand alternate contact of relay 10, and 65 through its left-hand alternate contacts, connects battery through the left-hand winding of supervisory relay 15 to the ring strand of the cord circuit, so that this supervisory relay 15 may be controlled by the switchhook contact at the station of the connected telephone line. A slow release relay 18 is momentarily energized, and answering supervisory lamp 19 is momentarily lighted 70 upon the energization of the marginal relay 75 10, over a circuit from battery, through left-hand alternate contact of marginal relay 10, normal contact of supervisory relay 15 and through the lamp 19 and the left-hand winding of relay 18 in parallel, to ground. Supervisory relay 15 is thereupon energized 80 over the talking circuit which includes the limbs of telephone line A. The energization of the supervisory relay 15 causes the de-energization of relay 18, and the extinguish- 85 ment of the lamp 19. Relay 9, in operating, closes its contact so that upon the release of relay 18, following the energization of supervisory relay 15, relay 16 is operated over a circuit from battery, through the normally 90 closed contact of listening key 17, the contact of relay 9, the winding of relay 16, right-hand normal contact of slow-release 95 relay 18, the alternate contact of supervisory relay 15, and through the left-hand 100 winding of relay 18 and the lamp 19 in 105

parallel to ground. Relay 18 is marginal, so that when its left-hand winding is shunted by the lamp 19, and is included in circuit with the winding of relay 16, it does not operate. Relay 16, however, in operating, immediately closes a locking circuit for itself through its left-hand contact, and the left-hand normal contact of relay 18 to ground. It will be seen, therefore, that immediately upon the operation of relay 16, the left-hand winding of relay 18 and the lamp 19 are both short-circuited through the normal contact of relay 18, and the left-hand contact of relay 18.

15 The operator may now actuate listening key 17 to connect the operator's telephone set with the cord circuit. Relay 16 is de-energized upon the actuation of this listening key. After having been advised by the 20 calling subscriber A that connection is desired with the subscriber of the local battery line B, the operator restores listening key 17 to normal position, and inserts plug 22 into jack 23 of line B, whereupon the cutoff relay 24 thereof is operated over a circuit from battery, through the right-hand winding of 25 relay 9, the winding of marginal relay 25, sleeve contacts of the plug 22 and the jack 23, and the winding of cutoff relay 24 to 30 ground. The winding of cutoff relay 24 is of high resistance so that marginal relay 25 does not operate. The restoration of the listening key 17 to normal position causes the 35 reenergization of relay 16, and the locking-up thereof over the previously traced circuit.

35 The operator may now actuate ringing key 26 to connect a source of ringing current 27 with the line, for operating the usual call bell at substation B. The subscriber, in 40 responding to the operation of the call bell, removes the receiver from the switchhook, and is in direct communication with the subscriber A through the cord circuit C.

At the conclusion of the conversation, the 45 subscribers restore their respective receivers to the switchhooks, and, in addition, subscriber B gives a short turn of the handle of generator 28 to give a disconnect signal. The operation of this generator causes the 50 energization of supervisory relay 30, which, in attracting its armature, causes the operation of relay 31 over a circuit from battery, through the contact of listening key 17, contact of relay 9, winding of relay 31, left-hand normal contact of slow-release relay 32, alternate contact of relay 30, and lamp 33 to ground. Relay 31, in operating, establishes a locking circuit for itself through its left-hand contact and the right-hand normal 55 contact of relay 32 to ground. Upon the release of supervisory relay 30 the lamp 33 is lighted over a circuit from battery, through the left-hand contact of relay 31, right-hand normal contact of relay 25, normal contact 60 of relay 30, and the lamp 33 to ground.

The right-hand winding of relay 32 is in parallel with the lamp 33, and this relay 32 is therefore operated, but performs no useful function at this time. The lighting of lamp 33 serves as a disconnect signal.

70 The restoration to the switchhook of the receiver at the subscriber's station A de-energizes the supervisory relay 15, thereby causing the operation of relay 18 over a circuit from battery, through the left-hand alternate contact of relay 10, normal contact of supervisory relay 15 and the left-hand winding of relay 18 to ground. Relay 18, in operating, opens a short circuit about its right-hand winding, whereupon relay 18 is 75 locked up through its right-hand winding in series with the winding of relay 16.

At the time the circuit is closed through the left-hand winding of relay 18, the lamp 19 is lighted, to furnish a disconnect signal. 80 The closure of the alternate contact of relay 18 connects an interrupter 34 to the front contact of the supervisory relay 15. If the subscriber A initiates a recall before the operator has withdrawn the plug 7 from the 85 jack 8, the consequent energization of the supervisory relay 15 causes the lamp 19 to be intermittently lighted over a circuit from battery, through the interrupter 34, the alternate contact of relay 18, the alternate 90 contact of supervisory relay 15 and the lamp 19 to ground. The intermittent operation of this lamp serves as a recall signal. The operator, upon observing the intermittent lighting of the supervisory lamp 19, may 95 100 actuate listening key 17 to connect the telephone set with the talking circuit. The actuation of the listening key 17 opens the locking circuit of relays 16 and 18, which thereupon release their armatures, extinguishing the lamp 19.

If subscriber A does not initiate a recall, the continuous lighted condition of the supervisory lamps 19 and 33 serves as a disconnect signal to the operator who may 110 withdraw the plug from the jack, thereby restoring all apparatus to normal condition.

Should subscriber A desire to be connected with a common battery line similar to line A, the operator then inserts the plug 115 22 into the jack associated with the common battery line. The cutoff relay of the common battery line being of low resistance, marginal relay 25 then operates. The operation of the relay 25 immediately connects battery and ground to the tip and ring conductors of the cord circuit, and causes the operation of relay 32 and the lighting of calling supervisory lamp 33 over a circuit from battery, through the 120 right-hand alternate contact of relay 25, normal contact of supervisory relay 30, and through the lamp 33 and the right-hand winding of relay 32 in parallel to ground.

125 The operation of relay 32 opens its left-

hand normal contact, which is in the initial energizing circuit of relay 31. In this manner the operation and locking up of relay 31 is prevented should supervisory relay 30 be momentarily energized by the discharge of the condenser connected with the line, upon the closure of the tip and ring conductors when the ringing key 17 is restored to normal position, after ringing the call bell 10 of the called-for line, or should the alternate contacts of the supervisory relay be momentarily disengaged, due to the bounding—so-called—of the armature when the supervisory relay is first energized.

15 The called subscriber, in responding to the operation of the call bell, resulting from the connection of ringing current to the line, removes the receiver from the switchhook, thereby causing the operation of supervisory relay 30. The lamp 33 is thereby extinguished, and the circuit which includes the right-hand winding of relay 32 is opened, whereupon the relay releases its armatures. Upon the closure of the left-hand normal contact of relay 32, relay 31 is operated over the hereinbefore traced circuit which includes the normal contact of the listening key 17, the contact of relay 9, the winding of relay 31, the left-hand normal contact of relay 32, the alternate contact of supervisory relay 30, the right-hand winding of relay 32 to ground. While the lamp 33 is included in parallel with the right-hand winding of relay 32, it does not light on account 35 of the high resistance of the winding of relay 31. Due to the same reason relay 32 does not attract its armatures. Relay 31, in operating, completes a locking circuit for itself through its right-hand contact, and 40 the right-hand normal contact of relay 32.

At the conclusion of the conversation the called subscriber, in restoring the receiver to the switchhook, causes the release of the supervisory relay 30, whereupon the lamp 33 is lighted, and the relay 32 is operated over a circuit from battery through the right-hand alternate contact of relay 25, normal contact of supervisory relay 30, and through the lamp 33 and the right-hand winding of 45 relay 32 in parallel to ground. Since the winding of relay 31 is not included in this circuit, the lamp 33 lights and the relay 32 operates. Immediately upon the operation of relay 32, the short circuit about its left-hand winding is removed, whereupon relay 32 is locked up in series with the winding of relay 31. Interrupter 34 is now connected with the alternate contact of relay 32, so that if the subscriber in initiating another call removes the receiver from the switchhook before the plug 22 is withdrawn from the jack, supervisory relay 30 is energized, whereupon the lamp 33 is intermittently lighted over a circuit from battery, 50 through the interrupter 34, the alternate

contact of relay 32 and the lamp 33 to ground.

Slow release relays 18 and 32 have precisely the same characteristics. Since each of these relays is slow releasing, the momentary energization of either of the supervisory relays, due to the discharge of the condenser on the line upon the restoration of the ringing key to normal position, is not sufficient to permit the release of the slow 70 release relay to close the contact in circuit with the recall control relay 16 or 31. In this way the appearance of a false recall signal is prevented. It will be understood that either end of the cord circuits may be employed as the answering end and either as the calling end.

What is claimed is:

1. A telephone exchange system comprising a telephone line, a link circuit, a relay therein responsive to the connection of the link circuit with the telephone line, a signaling device and a second relay in the link circuit, an energizing circuit for the second relay completed upon the response of the first relay, a supervisory relay in the link circuit, a recall control relay energized upon the energization of the supervisory relay and the deenergization of the second relay, interrupter mechanism, and a circuit including the interrupter mechanism and the signaling device completed upon the energization of the second relay, due to the deenergization of the supervisory relay followed by the energization thereof. 100

2. A telephone exchange system comprising a telephone line, a link circuit, a relay therein responsive to the connection of the link circuit with the telephone line, a signaling device and a second relay in the link circuit, an energizing circuit for the second relay completed upon the response of the first relay, a supervisory relay in the link circuit, a recall control relay energized upon the energization of the supervisory relay 110 and the deenergization of the second relay, and interrupter mechanism included in circuit with the signaling device when the recall control, supervisory and second relays are simultaneously energized. 115

3. A telephone exchange system comprising a telephone line, a link circuit, a relay therein responsive to the connection of the link circuit with the telephone line, a signaling device and a second relay in the link circuit, an energizing circuit for the second relay completed upon the response of the first relay, a supervisory relay in the link circuit, a recall control relay energized upon the energization of the supervisory relay 120 and the deenergization of the second relay, interrupter mechanism, and a circuit for the interrupter mechanism and the signaling device completed through a contact of the second relay when energized upon the de- 125

energization of the supervisory relay and through a contact of the supervisory relay when subsequently energized.

4. A telephone exchange system comprising a telephone line, a link circuit, a relay therein responsive to the connection of the link circuit with the telephone line, a signaling device and a second relay in the link circuit, an energizing circuit for the second relay completed upon the response of the first relay, a supervisory relay in the link circuit, a recall control relay energized upon the de-energization of the second relay while the supervisory relay is energized, a locking circuit for the recall control relay established upon the energization thereof for rendering this relay independent of the condition of the supervisory and second relays, interrupter mechanism, and a circuit for the interrupter mechanism and the signaling device partially completed upon the energization of the second relay when the supervisory relay is deenergized and fully completed by the subsequent energization of the supervisory relay.

5. A telephone exchange system comprising a telephone line, a link circuit, a signaling device therefor, a local relay energized upon the connection of the link circuit with the telephone line, a supervisory relay energized upon the closure of the telephone line, a recall control relay, an energizing circuit therefor completed upon the energization of the supervisory relay followed by the de-energization of the local relay, and interrupter mechanism included in circuit with the signaling device upon the subsequent energization of the local relay followed by the energization of the supervisory relay.

40 6. A telephone exchange system comprising a telephone line, a link circuit, a signaling device therefor, a local relay energized upon the connection of the link circuit with the telephone line, a supervisory relay energized upon the closure of the telephone line, a recall control relay, an energizing circuit therefor completed upon the energization of the supervisory relay followed by the de-energization of the local relay, interrupter mechanism, a circuit for the interrupter mechanism and the signaling device partially established upon the energization of the local relay when the supervisory relay is deenergized and fully established upon the subsequent energization of the supervisory relay.

7. A telephone exchange system comprising a telephone line, a link circuit, a signaling device therefor, a local relay energized upon the connection of the link circuit with the telephone line, a supervisory relay energized upon the closure of the telephone line, a recall control relay, an energizing circuit therefor completed upon the energization of the supervisory relay followed

by the deenergization of the local relay, interrupter mechanism, and an operating circuit for the signaling device including the interrupter mechanism and contacts of the local and supervisory relays when energized. 70

8. A telephone exchange system comprising a telephone line, a link circuit, a signaling device therefor, interrupter mechanism, a recall control relay adapted when energized to control the inclusion of the interrupter mechanism in circuit with the signaling device, a local relay energized upon the connection of the link circuit with the telephone line, a supervisory relay in the link circuit energized upon the closure of the telephone line to cause the deenergization of the local relay, an energizing circuit for the recall control relay established upon the deenergization of the local relay, and an operating circuit for the signaling device including the interrupter mechanism completed upon the subsequent energization of the local relay followed by the energization of the supervisory relay. 80

9. A telephone exchange system comprising a telephone line, a link circuit, a signaling device therefor, an interrupter mechanism, a recall control relay adapted when energized to control the inclusion of the interrupter mechanism in circuit with the signaling device, a local relay energized upon the connection of the link circuit with the telephone line, a supervisory relay in the link circuit energized upon the closure of the telephone line to cause the deenergization of the local relay, an energizing circuit for the recall control relay including contacts of the energized supervisory relay and the deenergized local relay, and an operating circuit for the signaling device including the interrupter mechanism completed upon the subsequent energization of the local relay followed by the energization of the supervisory relay. 95

10. A telephone exchange system comprising a telephone line, a link circuit, a signaling device therefor, an interrupter mechanism, a recall control relay adapted when energized to control the inclusion of the interrupter mechanism in circuit with the signaling device, a local relay energized upon the connection of the link circuit with the telephone line, a supervisory relay in the link circuit energized upon the closure of the telephone line to cause the deenergization of the local relay, an energizing circuit for the recall control relay including contacts of the energized supervisory relay and the deenergized local relay, a locking circuit for the recall control relay established upon the energization thereof for rendering this relay independent of the condition of the supervisory and local relays, and an operating circuit for the signaling device including the interrupter 110

105

115

120

125

130

mechanism partially established upon the energization of the local relay when the supervisory relay is deenergized and fully established upon the subsequent energization 5 of the supervisory relay.

11. A telephone exchange system comprising a telephone line, a link circuit, a signaling device and a supervisory relay in the link circuit, interrupter mechanism, a 10 recall control relay when energized coöperating with the supervisory relay to include the interrupter mechanism in circuit with the signaling device, and means in the link circuit responsive to the connection of 15 the link circuit with the telephone line to open a contact in the energizing circuit of the recall control relay thereby to prevent the energization of the recall control relay upon the momentary energization of the su- 20 pervisory relay.

12. A telephone exchange system comprising a telephone line, a link circuit, a signaling device and a supervisory relay in the link circuit, an interrupter mechanism, a recall control relay when energized co- 25 operating with the supervisory relay to include the interrupter mechanism in circuit with the signaling device, and a slow release relay in the link circuit energized upon the connection of the link circuit with the 30 telephone line and over a circuit including a contact of the deenergized supervisory relay, thereby to prevent the energization of the recall control relay upon the momentary energization of the supervisory relay. 35

In witness whereof I hereunto subscribe my name this 29th day of December, A. D. 1917.

DAWSON M. TAGGART.
